CIRCUIT BREAKER

James H. Burnside, 2nd, New York, N. Y., assignor, by mesne assignments, to Circuit Breakers, Inc., New York, N. Y., a corporation of New York

Application March 11, 1937, Serial No. 130,262

19 Claims. (Cl. 200—116)

The present invention relates to circuit breakers and embodies, more specifically, an improved form of a circuit breaker of the so-called plug type wherein the circuit breaker is adapted to be received within the standard form of receptacle now in use.

More particularly, the invention relates to the type of circuit breaker shown and described in applicant's co-pending application, Serial No. 104,895, filed October 9, 1936, for Circuit breaker, and this invention embodies certain important improvements by means of which the operation of breakers of this type is greatly facilitated.

An object of this invention is to provide a circuit breaker which is normally urged into an open position and held in closed position by an improved form of holding mechanism which is released by a bi-metal element, the holding mechanism being of such character as to cause it to hold the movable contact effectively in its closed position, at the same time permitting only a very slight pressure of the bi-metal element to release it from its holding position.

A further object of the invention is to provide an improved form of circuit breaker wherein the spring which urges the movable contact into an open position is effectively separated from the contact elements to prevent any injury to the spring by heat generated during operation.

30 A further object of the invention is to provide a circuit breaker of the above character having a spring to urge the same normally into an open position, the mechanism being of such character as to cause this spring to cushion the final opening motion of the movable breaker element.

35 A further object of the invention is to provide a circuit breaker of the above character wherein an effective wiping contact is preserved between a central terminal of the breaker and the adjacent end of a movable contact-carrying spindle.

A further object of the invention is to provide an improved circuit breaker of the above character wherein a rotatable member is provided within the breaker for carrying the movable breaker contact and effectively inclosing certain of the breaker elements therein.

40 A further object of the invention is to provide a circuit breaker having an improved operating mechanism by means of which the movable breaker contact may be moved into a closed position, such mechanism preventing the movable contact from being held in a closed position under over-load conditions.

45 A further object of the invention is to provide an operating mechanism for circuit breakers of

the above character wherein the movable breaker contact is actuated thereby by motion of the operating means intermittently in a continuous direction.

Further objects of the invention will be apparent as it is described in greater detail in connection with the accompanying drawings, wherein:

Figure 1 is a view in transverse section, taken on line 1—1 of Figure 3, and looking in the direction of the arrows; 10

Figure 2 is a view in horizontal section, taken on line 2—2 of Figure 1, and looking in the direction of the arrows;

Figure 3 is a view in horizontal section, taken on line 3—3 of Figure 1, and looking in the direction of the arrows; 15

Figure 4 is a view similar to Figure 3, showing the rotor in open position;

Figure 5 is a view taken on the broken section 20 line 5—5 of Figure 4;

Figure 6 is a plan view of the device in slightly reduced scale;

Figures 7, 8 and 9 are views in horizontal section taken on the line 4—4 of Figure 5 looking in 25 the direction of the arrows, the said figures showing the mechanism in "off," "reset" and "on" positions, respectively;

Figure 10 is a view in section showing the invention incorporated in an attachment plug. 30

Referring to the above drawings, a circuit breaker is shown as provided with a casing 20 having a threaded portion 21 and formed with a partition 22. The threaded portion 21 is formed with a chamber 23 and receives a threaded shell 35 24, which is adapted to be threaded into a suitable socket or receptacle. A lower cover 25 is provided for the chamber 23 and carries a central terminal 26 to which a leaf spring 27 is secured. The leaf spring 27 is reversely bent and formed 40 with a cup-shaped contact 28.

Within the partition 22 is received a spindle 29, the lower end of which is formed with a cap 30 which is received within the cup-shaped wiper or contact 28. A coil spring 31 is secured 45 at one end to the spindle 29 and, at its other end, to the spindle 29, the function of this spring being to urge the spindle 29 normally into an open circuit position. In this connection, it is important to observe that the spring 31 is of 50 such character as to expand against the cylindrical wall of chamber 23 when the spindle 29 approaches the final open circuit position, thus producing an effective cushioning action upon spindle 29 at such time.

The interior of casing 20 receives a rotatable cylindrical member 32, which is secured to the top of spindle 29 to rotate therewith. A stationary contact 33 is provided in the inner portion of casing 20, this contact being carried by a current-conducting member 34 having its lower portion 35 received within, and in electrical contact with, the shell 24. A graphite insert 36 is provided to prevent the destructive effect of arcing on the stationary contact 33.

The rotor 32 is formed with an inner chamber 37 and has secured thereto a cover plate 38 which encloses the mechanism within the chamber 37 to the top of the spindle 29, which is received within the chamber 37, a conducting plate 39 is secured by means of a screw 40. This conducting plate 39 carries a bi-metal element 41, the free end of which is formed with a curved pressure surface 42. A pigtail 43 connects the free end of the bi-metal element 41 with a movable contact 43 which is slidably received in the peripheral wall of the rotor 32. A spring 44 normally urges the contact 43 outwardly into the position shown in Figure 3, at which time the movable contact 43 engages the stationary contact 33. A graphite insert 45 is carried by the movable contact 43 to cooperate with the graphite insert 36 in preventing destructive arcing.

In order that the rotor may be held in a circuit-closing position, a detent 46 is slidably mounted therein and cooperates with a recess 47 in the wall of casing 20. This detent is moved axially by means of a toggle member 48, which is pivoted at 49 to the rotor 32. A spring 50 normally urges the toggle mechanism and detent into the position shown in Fig. 3, at which time the detent 46 engages the sloping surface 51 of recess 47 to prevent the opening of the circuit breaker. A shoulder 52 is provided by the recess 47 to engage the detent 46 and locate the mechanism in the closed position, as illustrated in Figure 3. It will thus be seen that an overload condition will cause the bi-metal element 41 to move outwardly and cause the pressure surface 42 to engage the toggle joint and release the same to permit the circuit breaker to open. Great accuracy results in view of the toggle mechanism by means of which a relatively slight force may be used to cause this opening motion, regardless of the friction or other conditions of wear between the detent 46 and the adjacent casing wall.

The movable contact 43 is provided with a pin 53 which is adapted to be engaged by a latch 54 which is pivoted at 55 to the rotor 32. A spring 56 normally urges the latch into a pin-engaging position and the latch is formed with an upwardly extending arm 57 by means of which it may be released, as will be described hereinafter. The casing 20 is formed with a cam track 58 which serves to move the contact 43 inwardly into a latched position, as illustrated in Figure 4. The latch 54 holds the slide contact 43 securely in position so that when it slides past the recess 47 it will not engage the shoulder 52 thereof and thus make further rotation of the member 32 impossible.

Extending upwardly from the cover 38 is a central shaft 59, in the peripheral surface of which a groove 60 is formed, the groove being provided with a shoulder 61. A pin 62 is secured to the shaft 59 and is provided with a head 63 upon which a pointer 64 is formed. Rotatably mounted upon the head 63 is a manually operable disc 65 which preferably is formed with its

periphery lying contiguous to the periphery of the casing 20. Within the casing 20 a cover 66 is provided, the cover being formed with an upwardly projecting circular flange 67 having serrations 68 formed on its inner periphery. The manually operable member 65 is formed with a leaf spring 69 which is adapted to engage the serrations 68 and thus permit rotation of the member 65 in one direction only, (clockwise, as illustrated in Figure 8).

Motion is transmitted between the member 65 and shaft 59 by means of a disc 70 which is pivoted at 71 to the under-side of the member 65. This disc is provided with a counter-clockwise bias by means of a spring 72 and is formed with an arm 73 which is adapted to engage the shoulder 61. A second arm 74 is formed on the disc 70 and is pivotally connected to a toggle lever 75, the other end of which is pivoted at 76 to the lower side of the member 65. The central pivot 77 of the toggle member 75 extends downwardly and is adapted to engage a cam 78 having an inclined face 79 and a circular face 80. The cam 78 is formed upon the cover 66, as illustrated in Figure 5, and the toggle lever 75 is biased in the position shown in Figure 8 by means of a spring 81. In this fashion, as illustrated in Figure 8, rotation of the member 65 causes arm 73 to transmit the motion of the member 65 to the shaft 59, thus turning the rotor 32. The cam 78 lies in the path of pin 71 to effect a sequence of operations to be described hereinafter.

Also formed upon the member 65 and depending downwardly therefrom is a trip member 82 which is adapted to engage the arm 57 to release the latch 54 and brush 43 on the toggle lever 48 in order that the rotor 32 may be manually released.

Upon the member 65 is mounted a plate 84, being suitably secured to the member in such fashion as to prevent relative rotation with respect thereto. Plate 84 is provided with suitable indicia which have herein been indicated at 85, 86, 87 and 88.

In operation, and in the position illustrated in Figures 1 and 3, the circuit breaker is in its closed position, at which time pointer 64 points to indicia 86 (on). When excess current flows through the bi-metallic arm 41, its pressure surface 42 moves the pin 83 on the toggle 48 outwardly, thus releasing the detent 46 and breaking the contacts 43 and 36. The tension in spring 31 causes the rotatable member 32 to rotate to the position shown in Figure 4, in which contact 43 is approximately 180° away from the position shown in Figure 3. During the rotation of the member 32, the contact 43 is moved inwardly by the cam surface 58 of the casing 20, until the latch 54 engages the pin 53.

To reset the circuit breaker, the member 65 is rotated in a clockwise direction. Such rotation of the member 65 causes the pin 71 to ride off the cam 78, at which time the toggle 75 assumes its normal position and the arm 73 engages shoulder 61. Further rotation of the member 65 moves the rotor 32, eventually bringing the detent 46 into engagement with the recess 47, at which time the pointer 64 points to indicia 85 (reset). This last position is shown in Figure 9. The circuit, however, is still not closed since the latch 54 has not been released to allow the contact 43 to rest against contact 36. This operation is accomplished by further rotation of the member 65 so that the cam surface of the stop 82 will engage the arm 57, thus moving it radially out-

wardly and releasing the latch 54. At this point the pointer 64 points to indicia 86 (on). The circuit breaker is now in the normal operating position and may be tripped by an overload, as described above.

The circuit may also be tripped manually by rotation of the member 65 beyond the "on" position. Such rotation causes the stop 82 to engage the pin 83 on the toggle 48, moving it outwardly and thus releasing the detent 46 and breaking the circuit as described above.

In Figures 7, 8 and 9, the arrow found within the outline of the shaft 59 indicates the relative position of the movable contact 43. The arrow outside of the member 65 and at the bottom of the figures indicates the relative position of the stationary contact 33. From Figures 7, 8 and 9, it will be observed that the toggle 80 and 81 and the plate 70 serve as the driving connection between the manually operable member 65 and the shaft 59. When the toggle 80 is in the position shown in Figures 7 and 8, the arm 73 on the plate 70 engages the adjacent shoulder on the shaft 59 forming the end of the cut-away portion 60. Turning the member 65 thus causes the shaft 59 to be turned and such driving connection is maintained until the pin 77 at the mid point of the toggle 80 rides up on the cam 78 as illustrated in Figure 9. This results in breaking of the toggle and the aforesaid driving connection. The point at which this break occurs will be apparent from Figure 8 in which position the pin is just beginning to ride up on the surface of the cam. When the toggle is broken as illustrated at Figure 9, the manually operable member 65 has no driving or holding connection with the shaft 59 and the free tripping mechanism is thus unaffected by the member 65.

A further feature of the invention resides in the adaptation of a circuit breaker of the type above described for use in connection with an attachment cord. This is illustrated in Figure 10 wherein the prongs of an attachment plug 90 are illustrated at 91 and 92. Prong 91 is formed with a central terminal 93 with which the contact 26 engages while the prong 92 is connected to one wire 94 of an attachment cord 95. The attachment cord may be carried by the plug 90 by means of a threaded cap 96, the other wire 97 of the cord being soldered to the shell 24. A screw or other fastening element 98 may be provided to secure the casing 20 to the plug 90, recesses 99 and 100 being provided in order that the various elements may be countersunk within the plug and covered over by a suitable wax or other sealing element.

I claim:

1. A circuit breaker comprising a stationary and a rotatable contact, a rotatable spindle upon which the rotatable contact is secured, bi-metal controlled means to hold the rotatable contact in closed position, actuating means to move the rotatable contact into a circuit-closing position, a casing to enclose the contacts, a partition in the casing upon one side of which the contacts are disposed, said spindle being journaled in the partition, and a spring on the other side of the partition to urge the rotatable contact normally into an open position.

2. A circuit breaker comprising a stationary and a rotatable contact, a rotatable spindle upon which the rotatable contact is secured, bi-metal controlled means to hold the rotatable contact in closed position, actuating means to move the rotatable contact into a circuit-closing position, a

casing to enclose the contacts, a partition in the casing upon one side of which the contacts are disposed, said spindle being journaled in the partition, a spring on the other side of the partition to urge the rotatable contact normally into an open position, a terminal in the casing on the last-named side of the partition, and a wiping contact between the terminal and the adjacent end of the spindle.

3. In a circuit breaker, the combination of a fixed contact, a rotatable contact, manual means for moving the rotatable contact into closed circuit position, a spring normally urging the rotatable contact into the open circuit position, bimetal controlled means for holding the rotatable contact releasably in the closed circuit position, a spring normally urging the rotatable contact into engagement with the fixed contact in the closed circuit position, latching means for holding the said rotatable contact releasably out of engagement with said fixed contact, and means for moving said rotatable contact into the latched position as the rotatable contact moves from the closed to the open circuit position.

4. A circuit breaker comprising a casing, a rotatable contact-carrying member in the casing, means to urge the member normally into an open position, means to move the member into a circuit closing position, a detent to hold the member in circuit-closing position, toggle mechanism to move the detent to a holding position, and means to engage the toggle mechanism to release the detent.

5. A circuit breaker comprising a casing, a rotatable control-carrying member in the casing, means to urge the member normally into an open position, means to move the member into a circuit-closing position, a detent on the member to hold the member in circuit-closing position, toggle mechanism to move the detent to a holding position, and means to engage the toggle mechanism to release the detent.

6. A circuit breaker comprising a casing, a rotatable contact-carrying member in the casing, means to urge the member normally into an open position, means to move the member into a circuit-closing position, a detent to hold the member in circuit-closing position, toggle mechanism to move the detent to a holding position, and bimetal means to engage the toggle mechanism to release the detent.

7. A circuit breaker comprising a casing, a rotatable contact-carrying member in the casing, means to urge the member normally into an open position, means to move the member into a circuit-closing position, toggle mechanism to move the detent to a holding position, a shoulder on the casing to be engaged by the detent and stop the member in circuit-closing position, and means to engage the toggle mechanism to release the detent.

8. A circuit breaker comprising a casing, a rotatable contact-carrying member in the casing, means to urge the member normally into an open position, releasable means to hold the member in a circuit-closing position, a manually operable member, means movably mounted on the manual member to engage and move the rotatable member, and means to move the engaging means to prevent movement of the rotatable member thereby.

9. A circuit breaker comprising a casing, a rotatable contact-carrying member in the casing, means to urge the member normally into an open position, releasable means to hold the mem-

- ber in a circuit-closing position, a manually operable member, a disc pivotally mounted on the manual member and having means thereon to engage the rotatable member, means to maintain the disc in engaging position, and means to render the last-named means ineffective to hold the disc in engaging position.
10. A circuit breaker comprising a casing, a rotatable contact-carrying member in the casing, means to urge the member normally into an open position, releasable means to hold the member in a circuit-closing position, a manually operable member, a disc pivotally mounted on the manual member and having means thereon to engage the rotatable member, toggle means to maintain the disc in engaging position, and means to render the last-named means ineffective to hold the disc in engaging position.
11. A circuit breaker comprising a casing, a rotatable contact-carrying member in the casing, means to urge the member normally into an open position, releasable means to hold the member in a circuit closing position, a manually operable member, a disc pivotally mounted on the manual member and having means thereon to engage the rotatable member, toggle means to maintain the disc in engaging position, and a cam to render the toggle means ineffective to hold the disc in engaging position.
12. A circuit breaker comprising a casing, a rotatable contact-carrying member in the casing, means to urge the member normally into an open position, releasable means to hold the member in a circuit-closing position, a manually operable member, a disc pivotally mounted on the manual member and having means thereon to engage the rotatable member, toggle means to maintain the disc in engaging position, means to bias the toggle means and disc in an engaging position, and a cam to render the toggle means ineffective to hold the disc in engaging position.
13. A circuit breaker comprising a casing, a rotatable contact-carrying member in the casing, means to urge the member normally into an open position, releasable means to hold the member in a circuit-closing position, a manually operable member mounted coaxially of the said rotatable member, means mounted movably on the manual member to engage and move the rotatable member, and a trip member on the manual member to engage the releasable means.
14. A circuit breaker comprising a casing, a rotatable contact-carrying member in the casing, means to urge the member normally into an open position, releasable means to hold the member in a circuit-closing position, a manually operable member mounted coaxially of the said rotatable member, means mounted movably on the manual member to engage and move the rotatable member, and a trip member on the manual member to engage the releasable means to hold the contact in an open position.
15. A circuit breaker comprising a casing, a rotatable contact-carrying member in the casing, means to urge the member normally into an open position, releasable means to hold the member in a circuit-closing position, a manually operable member means movably mounted on the manual member to engage and move the rotatable member, and means to permit motion of the manually operable member in one direction only.
16. A circuit breaker comprising a casing, a rotatable contact-carrying member in the casing, means to urge the member normally into an open position, releasable means to hold the member in a circuit-closing position, a manually operable member means movably mounted on the manual member to engage and move the rotatable member indicating means on the manually operable member, and cooperating indicating means on the rotatable member for indicating the actual position of the contacts.
17. In a circuit breaker, a support having a fixed contact thereon, a rotor journaled on the support having a contact thereon, a spring continually urging the rotor to contact disengaging position when the contacts are engaged, a rotatable actuator for moving the rotor to contact engaging position, means mounted on the rotor and cooperating with the said support to hold the rotor in contact engaging position, and an excess current actuated element for releasing the said last mentioned means whereby the spring moves the rotor to contact disengaging position.
18. In a circuit breaker, a support having a fixed contact thereon, a rotor journaled on the support having a contact thereon, a spring continually urging the rotor to contact disengaging position when the contacts are engaged, a rotatable actuator for moving the rotor to contact engaging position, latching means for holding the rotor in contact engaging position, and an excess current actuated element carried by said rotor for releasing the said latching means, whereby the spring moves the rotor to contact disengaging position.
19. In a circuit breaker a support having a fixed contact thereon, a rotor journaled on said support having a contact thereon, a spring continually urging the rotor to contact disengaging position when the contacts are engaged, a rotatable actuator for moving the rotor to contact engaging position, means mounted on the rotor and cooperating with said support to hold the rotor in contact engaging position, and an excess current actuated element carried by said rotor for releasing said last mentioned means whereby said spring moves said rotor in contact disengaging position.

JAMES H. BURNSIDE, 2ND.
